UNITED STATES PATENT OFFICE

2,606,371

RULER GAUGE

Leo J. Klimek, Long Prairie, Minn.

Application September 9, 1949, Serial No. 114,841

4 Claims. (Cl. 33—173)

1

This invention relates to an attachment for rulers and has for its primary object to enable an ordinary folding pocket rule or foot rule to be converted for use in connection with many varied types of layout or design work.

Another important object of this invention is to enable a ruler to be used for drawing circles, angles and designs normally requiring the use of angles or the like.

Another important object of this invention is to provide a simple and inexpensive ruler attachment that will not interfere with the folding of a folding pocket rule and that is adapted for operative attachment to any type of rule so that the rule can be utilized as a gauge, bevel or the like. These and ancillary objects are attained by this invention, the preferred embodiment of which is set forth in the following description and illustrated in the accompanying drawing, wherein:

Figure 1 is a fragmentary perspective view of a ruler, to which is attached the preferred embodiment of this invention;

Figure 2 is a longitudinal vertical sectional view taken on line 2—2 of Figure 1;

Figure 3 is a transverse sectional view taken on line 3—3 of Figure 1;

Figure 4 is a detailed sectional view taken on line 4—4 of Figure 2, and

Figure 5 is a top plan view showing the device attached to a ruler and utilized as a compass.

Referring now more particularly to the accompanying drawing, a conventional folding ruler 10 is illustrated and the attachment 12, which is constructed in accordance with the teachings of the instant invention, is detachably and slidably mounted thereon, the attachment functioning to convert the ruler for use as a gauge, angle, square or compass. The attachment includes a rectangular housing 14, which is preferably formed from a single piece of light but sturdy material. The housing is formed with opposing open ends and has an elongated top section 16 and a short bottom section 18, the latter sections being connected by vertical side walls 20 and 22. The housing is slidably disposed on the ruler and means is provided for locking the housing at desired points along the ruler.

For this purpose, the top wall or section 16 of the housing is formed with an elongated opening defined by downwardly directed parallel flanges 25 on which a channel-shaped member 24 is slidably disposed, the member being provided with a threaded vertical opening 26. A set screw 28 is threaded through the opening and has an

enlarged foot or plate 30 integrally formed on its inner or lower end, the foot being adapted to clamp on the upper face of the ruler and lock the housing thereon. To securely lock any type of ruler in the housing, regardless of the width of the ruler and to retain the housing in its proper axially aligned relationship with the ruler, spring leaves 32 and 34 are riveted as at 26 to the side wall 20 and bear against one side edge of the ruler holding the opposing side edge in abutting engagement of the side wall 22.

A base plate or supporting member 38 is provided for pivotally supporting the housing. The plate 38 is formed with a vertical section 40 and a horizontal section 42 disposed at right angles to the section 40. The plate is disposed transversely at one end of the housing and the horizontal section 42 is positioned on the top section 16 of the housing so that the beveled ends

10 44 of the side walls 20 and 22 extend to the elongated slot 46 in the upper end of the section 40. A protractor 48 is secured to the top section 16 and is interposed between the section 42 of the supporting plate and the top section.

15 A screw 50 extends vertically through the sections and a knurled locking nut 52 is disposed on the screw and seats on the section 42 to lock the housing in various angular positions on the supporting plate. It is to be noted that a pointer 54 is

20 44 of the side walls 20 and 22 extend to the elongated slot 46 in the upper end of the section 40. A protractor 48 is secured to the top section 16 and is interposed between the section 42 of the supporting plate and the top section. A screw 50 extends vertically through the sections and a knurled locking nut 52 is disposed on the screw and seats on the section 42 to lock the housing in various angular positions on the supporting plate. It is to be noted that a pointer 54 is

25 50 extends vertically through the sections and a knurled locking nut 52 is disposed on the screw and seats on the section 42 to lock the housing in various angular positions on the supporting plate. It is to be noted that a pointer 54 is

30 50 extends vertically through the sections and a knurled locking nut 52 is disposed on the screw and seats on the section 42 to lock the housing in various angular positions on the supporting plate. It is to be noted that a pointer 54 is

formed on the center of the free edge of the section 42 and cooperatively overlies the protractor carried by the housing.

Means is provided and is operatively carried by the housing for converting the ruler into a compass or similar instrument. Thus, a casing 56 is offset from and secured to the side wall 22, the casing being formed with apertured top and bottom walls 58 and 60. A pin 62 is vertically disposed through the apertured walls and is

35 40 formed with an axially enlarged shank section 64, which terminates in a ball 66 disposed above the top wall 58. A spring 68 is concentrically disposed about the pin between the shank section 64 and the bottom wall 60 to hold the pin

45 45 within the casing. Downward pressure on the ball 66 pushes the pin downwardly so that the housing and ruler secured therein move about the axis of the pin, as in Figure 5.

Thus, it can be seen that a compact and simple 50 attachment has been provided which will materially increase the uses and value of a ruler.

Having thus described the invention, what is claimed as new is:

1. An attachment for a ruler comprising an elongated housing having an open end and in-

cluding top and bottom walls connected by side walls for slidably receiving a ruler therein, a supporting member for said housing pivotally secured to the top wall adjacent one end thereof, means for securing the housing and the supporting member in adjusted angular relation, means adjustable longitudinally of the housing for securing a ruler in adjusted position in the housing, said last means including a plate disposed within and movable longitudinally of the housing and having engagement with the underside of the top wall, a clamping screw threaded through the plate, said top wall having a longitudinally extending opening therethrough, said screw being slidable in said opening.

2. An attachment for a ruler comprising an elongated housing having an open end and including top and bottom walls connected by side walls for slidably receiving a ruler therein, a supporting member for said housing pivotally secured to the top wall adjacent one end thereof, means for securing the housing and the supporting member in adjusted angular relation, means adjustable longitudinally of the housing for securing a ruler in adjusted position in the housing, said last means including the top wall having a longitudinally extending opening therethrough, said top wall having integral depending flanges extending along the side edges of the opening, a plate movably disposed in the housing having upwardly extending flanges along the opposite side edges thereof slidably and guidingly engaging the first mentioned flanges therebetween, a clamping screw threadingly extending through the plate, said screw slidably projecting through the opening and having its lower end adapted to bear against a ruler for urging the latter into frictional engagement with the bottom wall.

3. An attachment for a ruler comprising an elongated housing having an open end and including top and bottom walls connected by side walls for slidably receiving a ruler therein, a supporting member for said housing pivotally secured to the top wall adjacent one end thereof, means for securing the housing and the supporting member in adjusted angular relation, means adjustable longitudinally of the housing for securing a ruler in adjusted position in the housing, a leaf spring disposed in the housing and secured to one side wall thereof only and adapted to engage a ruler in the housing and yieldingly urge the same into engagement with the other

5 side wall, said last means including a plate movable longitudinally of the housing, a clamping screw threaded through the plate, said top wall having a longitudinally extending opening therethrough, said screw being slidable in said opening.

10 4. An attachment for a ruler comprising an elongated housing having an open end and including top and bottom walls connected by side walls for slidably receiving a ruler therein, a supporting member for said housing pivotally secured to the top wall adjacent one end thereof, means for securing the housing and the supporting member in adjusted angular relation, 15 means adjustable longitudinally of the housing for securing a ruler in adjusted position in the housing, said last means including a leaf spring disposed in the housing and secured to one side wall thereof only and adapted to engage a ruler 20 in the housing and yieldingly urge the same into engagement with the other side wall, the top wall having a longitudinally extending opening therethrough, said top wall having integral depending flanges extending along the side edges of the 25 opening, a plate movably disposed in the housing having upwardly extending flanges along the opposite side edges thereof slidably and guidingly engaging the first mentioned flanges therebetween, a clamping screw threadingly extending through the plate, said screw slidably projecting through the opening and having its lower end adapted to bear against a ruler for urging the latter into frictional engagement with the bottom wall, and a vertically reciprocable pin 30 mounted externally upon one side wall of the housing together with spring means supporting the pin at the upper extremity of its movement.
